ELECTRICALLY CONTROLLED LOCK

Harry A. W. Wehrs, Bangor, Wis.

Application March 28, 1938, Serial No. 198,559

8 Claims. (Cl. 70—141)

The object of the invention is to provide a lock for use on doors and similar closures by means of which the releasing operation is accomplished by the actuation in a predetermined sequence of a plurality of switches controlling locking or latching members; to provide a lock of the kind indicated in which a latch member is included as an element so that upon the releasing operation the latch may be thereafter actuated to release the closure; and generally to provide an electrically controlled lock of such construction that the elements may be readily reduced in number or increased in number to simplify or complicate the releasing operation.

With this object in view, the invention consists in a construction and combination of parts of which a preferred embodiment is illustrated in the accompanying drawings but to which the invention is not to be restricted. Practical application may dictate certain changes or alterations and the right is claimed to make any which fall within the spirit of the invention.

In the drawings:

Figure 1 is a horizontal sectional view on an enlarged scale of the improved lock, the wiring in certain of the parts being diagrammatically indicated.

Figure 2 is an enlarged sectional view of that portion of the construction including the latch member.

Figure 3 is a sectional view on the plane indicated by the line 3—3 of Figure 2.

Figure 4 is an enlarged sectional view of the cooperating ends of the bolt and bolt control bar.

Figure 5 is a sectional view on the plane indicated by the line 5—5 of Figure 4.

Figure 6 is a sectional view on the plane indicated by the line 6—6 of Figure 2.

Figure 7 is a sectional view of one of the double pole switches comprised in the complement of switches.

While the invention, in the proportioning of its parts may be constructed for mounting either on the door or in the jamb, it is illustrated in the present embodiment as being carried in the jamb, so that the latch 10 may enter the socket 11 in the door 12 when the latter is in closed position, the latch having the customary beveled nose 13 to depress it into its socket as the door moves to closed position. The latch 10 has a sliding mounting in the bolt 14 in a socket formed in the latter and which houses a spring 15 yieldingly impelling the latch to expose the nose end thereof, a fingerpiece 16 being exteriorly exposed for

the manual retraction of the latch when the bolt is in such a position to permit this. The bolt 14 has a slide mounting in guides 17 carried in the case 18 and the fingerpiece extends through a clearance slot 19 in the wall of the case. The bolt may occupy either of two positions in its guides, in one of which the closed end of the bore abuts the stem of the fingerpiece and precludes movement of the latch and in the other of which the latch is free to move the length of the slot 19 against the pressure of the spring 15. The stem of the fingerpiece is angular as shown, and the spring 15 surrounds a part of the stem and is compressed between the end of the latch and an abutment collar 20 fixed in the bore of the bolt. If desired, manual operation of the latch from either side may be provided by extending a fingerpiece similar to the fingerpiece 16 through an opposite side of the casing, so that there may be one on either side of the jamb or frame in which the lock is mounted.

The bolt 14 is yieldingly impelled into release position for the latch, being provided at the end remote from the latch with a stem 21 which passes through a guide bracket 22 and through the wall of the case 18, terminating in a head 23. Between a collar 24 and the bracket plate 22, the stem is surrounded by a compression spring 25 and when the bolt is in a position to prevent latch retraction, the spring is compressed. The head 23 of the stem serves as a fingerpiece by means of which the bolt is moved into latch holding position in which it is retained by a series of pawls 26, 27, 28, 29 and 30, the pawls 26 to 29 inclusive being spring impelled toward the bolt but the pawl 30 being without a spring, so that it will maintain either of the two positions in which it is set. Engagement of the pawls with the bolt is by means of seats formed in the latter resulting from notching the same but the spacing of successive seats is progressively increased while the spacing of the pawls is uniform. Thus, when the pawl 26 is engaged, the remaining pawls, except pawl 30, while in their respective notches, are spaced from the abutment ends. This, so that when the pawl 26 is released, the bolt will be withdrawn until the pawl 27 engages the abutment end of its notch and when it is released the pawl 28 engages the abutment end of its slot and so on.

The pawls are all pivotally mounted in the case and the retraction of the pawl 26 is accomplished by energizing the magnet 31. The magnet 32 performs a similar function for the pawl 27, the magnet 33 for the pawl 28 and the magnet 34

for the pawl 29. The pawl 30 is normally disengaged from its seat in the bolt 14 and is moved into engagement with its seat by energizing the magnet 35. Release of the pawl 30 from its seat is effected by movement of the bolt control bar 36 which is spring impelled in one direction through the instrumentality of a spring 37 surrounding a stem 38 on the bar and compressed between a collar 39 on the bar and a bracket plate 40 through which the stem slidably passes. The bolt control bar 36 is mounted in guides 41 carried in the casing and is provided with a fingerpiece 42 which extends through a slot 43 in the wall of the casing. The purpose of the fingerpiece is to move the control bar in a direction opposite to that in which it is moved with the spring.

The bolt control bar is retained in a position intermediately between its two extreme positions through the instrumentality of pawls 44, 45, 46 and 47 which are pivotally mounted and spring impelled toward the control bar to engage in seats in the latter similar to seats formed in the bolt. These seats are provided by notching the bar and progressively spacing the distance between successive notches, so that with uniformly spaced pawls, the bolt control bar may be released by successively retracting the pawls, allowing it to recede in short steps until it is finally entirely retracted when the pawl 47 is released.

The pawls 44 to 47 inclusive are successively retracted by successively energizing the magnets 48, 49, 50 and 51.

The bolt control bar is provided with a stem 52 terminating in a yoke 53 which extends around the ends of a finger 54 projecting laterally from a pull-rod 55 connected with the pawl 30 at the tail of the latter. The pull-rod 55 extends through the wall of the case and terminates in a head 56 and interior to the case is provided with a collar 57 for cooperation with a fork later described.

With the bolt control bar in its intermediate position or that in which it is retained by the pawl 44 when the latter is engaged with its seat, the stem side of the yoke 53 abuts the finger 54, so that if the control bar is moved further than this position, as it may be when the magnet 58 is energized, the pawl 30 will be moved into seat engaging position, when the finger 54 will abut the opposite side of the yoke when the bar returns to its intermediate position, or that in which it is retained by the pawl 44. When the pawl 30 is in bolt engaging position, the release of the control bar will then result in a pull against the finger 54 in an opposite direction than previously with the result that the pawl 30 will be retracted from its bolt engaging position.

Each of the pawls, except the pawl 47, is operatively connected with a circuit closer of which each is in the form of a longitudinally movable bar with alternate insulating and conducting zones. Movement of the bars as a result of pawl movement thus effects a switching operation and the bars in effect are switches and hereinafter are so referred to. There are thus provided the single-pole double-throw switches 59, 60, 61, 62, 63 and 64, the single-pole single-throw switch 65 and the double-throw switch 66 which is single pole in one position and double pole in the other.

The fork 67 which is the fork cooperating with the collar 57 is mounted within the case and slides in a guide 68, being shifted into and out of obstructing position with respect to the collar 57 through the medium of a hand knob 69.

The circuits of the several magnets above referred to are controlled by the switches 70, 71, 72, 73, 74, 75 and 76 of which all but switches 73 and 75 are single-pole, these two latter switches being double-pole. Blind switches 77 and 78 are provided to complicate the system to make it more difficult for one not acquainted with the sequence of operation of the switches to release the lock. The operation of either the switches 77 or 78 will effect bolt engaging operation of the pawl 30 at the wrong instance so that bolt release cannot thereafter be effected without the return of all parts to normal position.

Exteriorly, all of the switches, 70 to 78 inclusive, appear the same but they are promiscuously arranged so that their sequence of position will be at variance with their sequence of operation.

In operation, when the door 12 is closed and engaged by the latch 10, the latch is secured against retraction when the bolt 14 is in the forward position where the pawls 26, 27, 28 and 29 engage in their seats, as shown in Figure 1 of the drawings. The pawl 30, however, is in retracted or disengaged position. The latches 44 to 47, however, engage in their seats in the control bar in which position the upper side of the yoke 53 engages the finger 54 of the pull-rod 55. To release the bolt, the switches 70 to 76 inclusive must be operated in a certain sequence but in order that they may operate, the main control switch 79 must first be closed, this being a switch in one side of the main line conductor 80. With the switch 79 closed, if the switch 72 be first depressed, it will close the circuit on the magnet 31, current flowing over the conductor 80 to the switch 65 which is in closed position when the pawl 30 is retracted, then over the conductor 81 to the switch 72, then over the conductor 82 to the magnet 31, then over the conductor 83 through one pole of the switch 66 which is in closed position on the double-pole side, then over the conductor 84 to the return line 85. The pawl 26 will then be retracted and the bolt will move back a small distance until the pawl 27 engages the abutment face of its notch. Then the magnet 32 must be energized to effect release of the pawl 27 and this is accomplished by actuation of the switch 70, depressing which results in the flow of current over the conductor 80, switch 65 and conductor 81 as before, then through the switch 70, then over the conductor 85, then through the switch 66 which, by previous movement of the pawl 26, releases the switch from the double-pole side and closes it on the single-pole side. From the switch 66, current flows over the conductor 87 to the magnet 32 and thence over the conductor 88 to the return side of the line 85. The pawl 27 is then retracted and the bolt 14 drops back until further movement is arrested by the pawl 28 to release which the magnet 33 must be energized. This is accomplished by actuation of the switch 74, current passing as before to the conductor 81 and thence through the switch 74 to the conductor 89, thence through the switch 64 which, by the movement of the pawl 27, has been shifted to closed circuit position for this conductor. From the switch 64 current passes over the conductor 90 through the magnet 33 and over the conductor 91 to the return line 85. The pawl 28 is then retracted and the bolt drops back a further increment until it is arrested by the pawl 29. But the release of this pawl is not the next step in the series of operation. The pawl 30 must be moved into arresting position and this is done by energizing the magnet 35 which 75

is accomplished by the actuation of the switch 71. Current which reaches the conductor 81 as previously described, passes through the switch 71, over the conductor 92, through the switch 63 which, by movement of the pawl 28, has been moved into circuit closing position for this conductor. Thence current passes over the conductor 93 to the magnet 35 and thence to the return conductor 85. The pawl 30 is then moved into bolt engaging position and its associated switch 65 is shifted to open position, so that when the pawl 29 is released the bolt 14 will be arrested by the pawl 30 but it recedes a small amount to engage the pawl 30 after the release of the pawl 29 to prevent reengagement of the latter pawl with its seat after the magnet 34 is deenergized. To energize the magnet 34 to release the pawl 29 the switch 73 is operated. This is a double-pole switch but in this instance its circuit closing function is performed only on one side, current passing over the conductor 80 through the conductor 94, thence through the switch 62 which with the pawl 29 engaged is in circuit closing position for this conductor, thence over the conductor 95 to one pole of the switch 73, thence over the conductor 96, the conductor 97, the magnet 34 and the conductor 98 to the return conductor 85. The pawl 29 is thus retracted but, as before explained, the movement of the bolt beyond a small increment is arrested by the pawl 30.

The next series of operations calls for the successive release of the pawls 44 to 47 inclusive of the control bar 36. To release the pawl 44, the magnet 48 must be energized and this is done by the operation of the switch 75 which is also a double-pole switch, current flowing, when this switch is depressed, over the conductor 80 to the conductor 99, thence over the switch 62 which, by reason of the shift-over effected by movement of the pawl 29, is in circuit closing position for this conductor. From the switch 62 current flows over the conductor 100, the conductor 101, one side of the switch 75, the conductor 102, the magnet 48 and thence to the return conductor 85. The pawl 44 is thus released and the control bar 36 recedes until it is arrested by the pawl 45, to release which the magnet 49 is energized. This is accomplished by actuation of the switch 73. In this operation, the opposite pole than that previously active carries out the circuit closing function, current which reaches the conductor 101 in the same manner as previously described passing over the conductor 103 and through the switch 61 to the magnet 49, this switch being moved into circuit closing position for the magnet by the retraction of the pawl 44. Leaving the magnet 49 current passes over the conductor 104, at one pole of the switch 73, the conductor 105 and the conductor 106 to the return conductor 85.

The next step is to energize the magnet 50 to effect retraction of the pawl 46 which at this instance is restraining the control bar 36. Depression of the switch 76 results in closing the circuit on the magnet 50, the switch 60 having been moved into circuit closing position for this purpose by the retraction of the pawl 45. Current reaching the conductor 100 as previously described, passes over the conductor 107 to the switch 76, thence over the conductor 108 to the magnet 50, thence through the switch 60 over the conductor 109 to the conductor 106 and thence to the return conductor 85. The pawl 46 is thus withdrawn from its seat in the control bar and the latter moves a small distance until

it is arrested by the pawl 47 to retract which the magnet 51 must be energized. The switch 75 is closed for this purpose, the switch 59 having been moved into circuit closing position for the magnet 51 upon retraction of the pawl 46. When the switch 75 is depressed under these conditions, current flows over the conductor 100 to the opposite pole than that which was active in the previous operation, thence over the conductor 110, the switch 59, the magnet 51 and the conductor 106 back to the return conductor 85. The pawl 47 is then retracted and the spring 37 left free to retract the control bar 36 its full distance, when the yoke engages the finger 54 and effects retraction of the pawl 30 from the bolt 14, leaving the spring 24 of the bolt free to retract the latter when the latch is free to be released by finger movement applied through the knob 16.

It will be noted that the series of operations is carried out through the instrumentality of serially connected switches, a pawl actuated switch cooperating with a finger or hand actuated switch, so that both must be in their proper positions in order for the hand actuated switch to operate.

Assume that the switches were not actuated in proper sequence, then a pawl controlled switch would be in open circuit position and the magnet associated with the particular hand controlled switch could not be operated. For example, suppose that the switch 72 were first operated which, in the particular arrangement shown, is the first in the sequence of operations. This would result in withdrawing the pawl 26 from the bolt. But suppose the switch 71 were next operated. This could not energize its associated magnet 35 because the circuit on that magnet would be open by reason of the position of the switch 63. But the magnet 35 could be energized by depression either of the switch 77 or the switch 18. If the former, current would flow over the conductor 81 to the switch 77, thence over the conductor 111 from which it would pass to the conductor 112 through either the switches 63, 64 or 66, depending on whether any or all of the pawls 26, 27 and 28 are in bolt engaging position. Any of these three pawls in bolt engaging position would have its operatively connected switch in position to close the circuit between the conductors 111 and 112 through the conductors 113, 114 or 115. Any current flowing in the conductor 112 would pass through the magnet 58 and thence to the return conductor 85 through the conductor 116. Energizing the magnet 58, however, results in movement being imparted to the control bar in a direction to apply a pressure upon the finger 54 to move the pawl 30 into bolt engaging position. When this is done, the switch 65 is moved into open circuit position and if either of the pawls 26, 27 or 28 is engaged with the bolt at that time, magnetic release of such pawl will be precluded, since the switch 65 controls circuit continuity between the conductors 80 and 81. With any or all of the pawls 44, 45 and 46 engaged in their seats in the control bar 36, the switches 61, 60 and 59 are in circuit closing position through the conductors 117, 118 and 119 to place the conductor 120 in circuit with the conductor 121, so that if the switch 78 be closed, the magnet 58 will be energized either by current flowing from the conductor 107 through the switch 78 to the conductor 120 and thence over the conductor 121 to the magnet 58 or from the conductor 81 to the conductor 120, depending on the positions of pawls 29 and 30, since the 75

bolt releasing position of the pawl 29 will determine whether current can reach the switch over the conductor 100 and the similar position of the pawl 30 will determine whether it can reach the switch over the conductor 81. If the pawls of the control bar are not released in proper sequence the control bar will not be released and if the switch 78 be actuated, any pawls that have been previously released will be returned to control bar engaging position because the energization of the magnet 58 will impart movement to the control bar to effect this as well as to shift the pawl 32 into bolt retaining position.

To provide for quick operation of the bolt by someone from the inside of the protected enclosure, a multi-pole switch 122 is provided, all of the poles of this switch being connected together to the line 80 but the other poles being connected to the conductors 123, 124, 125 and 126 which lead respectively to the magnets 31, 32, 33 and 34. Closing the switch will result in current flowing simultaneously to these several magnets thus effecting retraction of all of the pawls so that the bolt may be retracted by its spring.

The fork 67 is of a form to adapt it to engage on either side of the collar 57. In one position, it is free of the collar and the pull-rod 55 may be moved in either direction to engage the pawl 30 with the bolt or disengage it therefrom. When the pawl is engaged with the bolt, the fork may be shifted into a position to overlap the collar 57 on one side, so that the pawl cannot then be retracted. When the pawl is disengaged, the fork may be shifted to engage the collar 57 on the other side to prevent engagement of the pawl with the bolt. By this arrangement the pawl 30 may be rendered operative to limit the operation of the mechanism to release pawls 26 to 29 inclusive. Or the fork may be employed to lock the pawl in the bolt so that the whole apparatus is rendered inoperative so far as release by the switches 70 to 76 is concerned.

The invention having been described, what is claimed as new and useful is:

1. A lock having a bolt, a spring yieldingly impelling the bolt from bolting position, a plurality of pawls yieldingly impelled toward the bolt and engaging seats in the latter to retain the bolt in bolting position, electrically actuated retracting means for each of said pawls, and a plurality of switches individually controlling the electrically actuated retracting means and having their sequence of operation at variance with their sequence of position.

2. A lock having a bolt, a spring yieldingly impelling the bolt from bolting position, a plurality of pawls yieldingly impelled toward the bolt and engaging seats in the latter to retain the bolt in bolting position, electrically actuated retracting means for each of said pawls, a plurality of manual switches for controlling the actuation of said retracting means, and a plurality of pawl actuated switches also controlling said retracting means and coordinated with the manual switches.

3. A lock having a bolt, a spring yieldingly impelling the bolt from bolting position, a plurality of pawls yieldingly impelled toward the bolt and engaging seats in the latter to retain the bolt in bolting position, electrically actuated retracting means for each of said pawls, a plurality of manual switches for controlling the actuation of said retracting means, and a plurality of pawl actuated switches also controlling said retracting

means and coordinated with the manual switches, the manual switches having their sequence of operation at variance with their sequence of position.

4. A lock having a bolt, a spring yieldingly impelling the bolt from bolting position, a plurality of pawls yieldingly impelled toward the bolt and engaging seats in the latter to retain the bolt in bolting position, the pawls and seats being arranged in series of which the spacing of the units of one is uniform and the spacing of the other progressively increased, so that bolt retention at any instant is due solely to one pawl, electrically actuated retracting means for each of said pawls, and a plurality of switches individually controlling the electrically actuated retracting means and having their sequence of operation at variance with their sequence of position.

5. A lock having a bolt, a spring yieldingly impelling the bolt from bolting position, a plurality of pawls yieldingly impelled toward the bolt and engaging seats in the latter to retain the bolt in bolting position, the pawls and seats being arranged in series of which the spacing of the units of one is uniform and the spacing of the other progressively increased, so that bolt retention at any instant is due solely to one pawl, electrically actuated retracting means for each of said pawls, a plurality of manually actuated switches individually controlling the electrically actuated retracting means and having their sequence of operation at variance with their sequence of position, and a plurality of pawl actuated switches coordinated with the manual switches to control the retracting means jointly with the switches.

6. A lock having a bolt, a spring yieldingly impelling the bolt from bolting position a plurality of pawls yieldingly impelled toward the bolt and engaging seats in the latter to retain the bolt in bolting position, an additional pawl normally disengaged from the bolt but engageable with a seat in the latter, electrically actuated retracting means for the yieldingly impelled pawls, electrical actuating means for said additional pawl, and a plurality of switches individually controlling all of said electrically actuated means and having their sequence of operation at variance with their sequence of position.

7. A lock having a bolt, a spring yieldingly impelling the bolt from bolting position, a plurality of pawls yieldingly impelled toward the bolt and engaging seats in the latter to retain the bolt in bolting position, an additional pawl normally disengaged from the bolt but engageable with a seat in the latter, electrically actuated retracting means for the yieldingly impelled pawls, electrical actuating means for said additional pawl, and a plurality of switches individually controlling all of said electrically actuated means and having their sequence of operation at variance with their sequence of position, and a pawl retained spring impelled control bar provided with electrical releasing means for the pawls, and a plurality of manually actuated switches controlling the last said release means and likewise having their sequence of operation at variance with their sequence of position, the control bar when released effecting the release of the said additional pawl when the latter is in bolt engaging position.

8. A lock having a bolt, a spring yieldingly impelling the bolt from bolting position, a plurality of pawls yieldingly impelled toward the bolt and engaging seats in the latter to retain

the bolt in bolting position, an additional pawl normally disengaged from the bolt but engageable with a seat in the latter, electrically actuated retracting means for the yieldingly impelled pawls, electrical actuating means for said additional pawl, and a plurality of switches individually controlling all of said electrically actuated means and having their sequence of operation at variance with their sequence of position, 5 10 and a pawl retained spring impelled control bar provided with electrical releasing means for the

pawls, and a plurality of manually actuated switches controlling the last said release means and likewise having their sequence of operation at variance with their sequence of position, the control bar when released effecting the release 5 of the said additional pawl when the latter is in bolt engaging position, the said additional pawl being provided with a manual latching means to positively retain it in either bolt engaging position or in a position disengaged from said bolt. 10
